UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

FARM TILE-DITCHER.

1,187,036.

Specification of Letters Patent. Patented June 13, 1916.

Application filed May 2, 1913. Serial No. 765,064.

To all whom it may concern:

Be it known that I, MORTON G. BUNNELL, a citizen of the United States of America, and resident of Chicago, Cook county, Illinois, have invented a certain new and useful Improvement in Farm Tile-Ditchers, of which the following is a specification.

My invention relates to excavators of that particular kind in which means are provided for cutting a trench as the machine moves along, as, for example, those known as farm tile ditchers, and more especially to machines of this class in which an endless series of buckets is employed for cutting the trench, and in which means are provided for automatically discharging the load from each bucket at the proper time.

Generally stated, the object of my invention is to provide a novel and highly efficient trenching machine of the foregoing general character.

Special objects are to provide novel and effective means for ejecting the load from the buckets, and for automatically cleaning the ejecting means to provide novel and effective mechanism for operating the endless series of buckets, permitting bodily up and down adjustment thereof to vary the depth of the ditch in which the tile is to be laid; and to provide certain details and features of improvement tending to increase the general efficiency of an excavator of this particular character.

To these and other useful ends my invention consists in matters hereinafter set forth and claimed.

In the accompanying drawings, Figure 1, is a side elevation of a trenching machine embodying the principles of my invention. Fig. 2, is a detail view, on a still larger scale, of the bucket dumping mechanism. Fig. 3, is an underneath plan of the bucket shown at the top of Fig. 4. Fig. 4 is a section on line 6-6 in Fig. 2.

As thus illustrated, my invention comprises a body frame A upon which the various operative parts are suitably mounted, and which in turn is supported by wheels B. The auxiliary frame C slides up and down in the guides e, and is provided with upper and lower sprockets c¹ and c², and the dumping sprockets c³. Sprocket chains D are arranged to travel around said

sprockets, and are provided with buckets E, which latter are secured at e upon said chains, whereby the fastenings e, which may be brackets, provide a movable mounting for each said bucket. Each bucket is provided with a pivoted ejector e¹ the pivot of which is located at e², and each ejector has an arm e³. These arms e³ are of such length, and the sprockets are of such diameter, that the axes of said sprockets, consisting of journals or shafts c⁴ and c⁵, do not engage said arms as the buckets move around their path of travel. The sprockets c³ are, however, of such diameter that the axis c⁶ thereof is in the path of travel of the arms e³, said axis consisting of an eccentrically mounted cylinder, as shown in Fig. 4. This cylinder serves not only as an axis for the sprocket wheels c³ but also as a cam, and as the arms e³ strike it, the ejectors e¹ are moved from the back to the mouth of each bucket, thereby discharging the load. The eccentricity of said cam relative to the axis of rotation of said sprocket wheels c³ as shown, is such that the ejector is forced out of the bucket by the time the latter is turned upside down, as shown in dotted lines in Fig. 4. This cam cylinder may be turned to the desired position and then fastened in place at its ends, in any suitable manner, on the vertically movable frame.

The load is dumped upon the apron or conveyer E, which may be of any suitable construction. An idler G supports the chains D between the sprockets c² and c³. The conveyer E is driven by a sprocket connection H with the shaft c⁴ of the upper sprockets c¹.

The chains D are driven by a gearing d, which latter is in turn driven by a sprocket connection I of any suitable character. This connection I is driven by another connection J, which latter connects with the engine K. The sprocket connection i is supported by a link i¹ pivoted on the frame C at i², and pivotally connected at i² with the upper end of the vertical link M, which latter is mounted to swing on the engine shaft i³. With this arrangement the frame C may move up and down without impairing the operativeness of the power transmitting connection by which the buckets are driven. Any suitable means can be em-

ployed for securing the frame C at different heights on the guides c, whereby the depth of the ditch is varied.

Another feature of my invention consists 5 in the means for automatically cleaning the ejectors e^1 . This comprises the scraper N which is mounted on the arms n, which latter are pivoted at n^1 , on a suitable portion of the frame, such as arms O, and provided 10 with a counter weight n^2 by which said scraper is restored to normal position. Any suitable means may be employed for holding 15 the scraper N in normal position, such as the stop n on the pivot n^1 , which limits the return movement of said scraper. The scraper N engages the ejectors e^1 , as shown in Fig. 4, and cleans the surface thereof, the said scraper swinging outward to allow the buckets to pass; and the cleaning operation 20 occurs during this outward swing. The load falls between the arms O, being received by said conveyer.

The buckets E may be of any suitable construction. As shown, each bucket is provided 25 with an open back having flanges e^4 against which the ejector e^1 , which is in the form of a flat plate, bears when the bucket is loaded.

What I claim as my invention is:—

30 1. A trenching machine comprising an endless series of excavating buckets, a movable mounting for each bucket, a pivoted ejector for each bucket, an arm for each bucket, rigid with the ejector thereof, and means in the path of said arms to operate the ejectors, together with upper and lower wheels for said series of buckets, the lower wheels being of a diameter to prevent said arms from intersecting the axis thereof, and 35 said upper wheels being of less diameter to enable said arms to engage said means.

2. A trenching machine comprising an endless series of excavating buckets, a movable mounting for each bucket, a pivoted 40 ejector for each bucket, an arm for each bucket, rigid with the ejector thereof, means in the path of said arms to operate the ejectors, and a scraper for cleaning said ejec-

tors, said scraper being movable out of the path of travel by the pressure of the ejectors thereon. 50

3. A trenching machine comprising an endless series of excavating buckets, a movable mounting for each bucket, a pivoted ejector for each bucket, an arm for each 55 bucket, rigid with the ejector thereof, means in the path of said arms to operate the ejectors, and a pivoted scraper for cleaning said ejectors, said scraper being movable out of the path of travel by the pressure of the 60 ejectors thereon.

4. A trenching machine comprising an endless series of excavating buckets, a movable mounting for each bucket, a pivoted ejector for each bucket, an arm for each 65 bucket, rigid with the ejector thereof, means in the path of said arms to operate the ejectors, a pivoted cleaner for said ejectors, movable about a horizontal axis by the pressure thereon of said ejectors, and means for 70 automatically restoring said cleaner to normal position.

5. A trenching machine comprising an endless series of excavating buckets, a movable mounting for each bucket, a pivoted 75 ejector for each bucket, an arm for each bucket, rigid with the ejector thereof, means in the path of said arms to operate the ejectors, and means for cleaning said ejectors, movable out of the path of travel by the 80 pressure thereon of said ejectors while said arms engage said means.

6. An excavating machine comprising a bucket, an ejector for said bucket, a scraper for cleaning said ejectors, said bucket having traveling motion relative to said scraper, said scraper being arranged to yield to the forward pressure of each ejector, and means for successively holding said ejectors in position to push the scraper out of the way. 90

Signed by me at Chicago, Illinois, this 22nd day of April, 1913.

MORTON G. BUNNELL.
